WATERPROOF SNAPBACK WATCHCASE

Hyman Dinstman, New York, N. Y., assignor to
I. D. Watch Case Co., Inc., New York, N. Y.

Application April 27, 1953, Serial No. 351,425

6 Claims. (Cl. 58—90)

1

This invention relates to new and useful improvements in waterproof watch cases.

More particularly, the present invention proposes the construction of an improved waterproof watch case with a readily removable back, which case can be opened and re-sealed simply by pressing the back again in place.

Another object of the present invention proposes forming the watch case with an annular body having an integral bezel and having a lower edge adapted to receive a back and a gasket sheet so that the back will be frictionally sealed in place merely by pressing it on the lower edge portion of the body over the gasket sheet.

Still further, the present invention proposes constructing the back with an upturned flange having a knife edge and constructing the body with a ledge overhanging its back receiving portion for the knife edge to bear against and sever the gasket sheet at the knife edge so that oversize gaskets may be cut to proper size and concealed from view inside the watch case.

As a further object, the present invention proposes constructing the watch case with a spring pad movement holder which will fit inside the case and hold the movement securely therein and which, in addition, will press against the gasket sheet and bias it toward the back to draw it tightly against the overlapping back flange and back receiving portion of the body.

The present invention further proposes a novel arrangement of the back flange and the back receiving portion of the body so that a thermoplastic gasket sheet will be securely held therebetween to tightly and simply seal the back to the body.

For further comprehension of the invention, and of the objects and advantages thereof, reference will be had to the following description and accompanying drawings, and to the appended claims in which the various novel features of the invention are more particularly set forth.

In the accompanying drawings forming a material part of this disclosure:

Fig. 1 is an enlarged sectional view of the watch case of the present invention.

Fig. 2 is a top plan view of the watch case with fragments of the strap or band shown.

Fig. 3 is a bottom perspective view of the movement holding spring pad used in this watch case.

Referring more particularly to the drawings, the watch case of the present invention has an annular body 15. The body 15 has an integral bezel 16 at its upper edge and a back receiving portion 17 at its lower edge.

The back receiving lower edge portion 17 is arcuately curved and the body 15 has on its outer

2

side a ledge portion 18 which overhangs the back receiving lower edge portion.

A back 19, preferably of stainless steel, has an annular upturned flange 20 which is of a diameter frictionally to seat on the back receiving portion 17 of the annular body 15. The upturned flange 20 on the back 19 has an upper knife edge 21.

Bezel 16 is provided with a groove 22 to receive crystal 23 and a stem receiving crown bushing 24 extends through the annular body 15 to movement 25 of the watch.

A resilient sheet gasket 26 extends across the body 15 and is frictionally secured between the annular flange 20 of the back 19 and the back receiving portion 17 of the body 15 to seal the back to the body. The sheet gasket may be made of thermoplastic sheeting such as Vinylite.

Movement 25 is held in the case by a spring pad movement holder 27 adapted to fit in the body 15 and press against the gasket 26 biasing it toward the back 19.

The movement holder 27 is a ring with an upturned outer peripheral edge and spaced downwardly bent ears 28 projecting from its inner peripheral edge for gasket abutment.

Sheet gasket 26 before insertion into the case preferably are oversized so that when the back 19 is pressed on the body 15 the knife edge 21 on the flange 20 of the back bears against the gasket and the ledge portion 18 overhanging the back receiving lower edge portion 17 of the body and severs the gasket at the knife edge. The excess gasket material which is sheared off is indicated in dot-dash outline at 28'.

The arcuately curved lower edge portion 17 of body 15 presses the gasket sheet 26 against the inside of the upturned flange 20 of back 19 at the point of tangency and the spring pad movement holder 27 provides enough tension on the gasket 26 to insure a tight seal.

Body 15 of the watch case is also provided with strap or band holding members 29 to which is secured the band 30.

While I have illustrated and described the preferred embodiment of my invention, it is to be understood that I do not limit myself to the precise construction herein disclosed and the right is reserved to all changes and modifications coming within the scope of the invention as defined in the appended claims.

Having thus described my invention, what I claim as new, and desire to secure by United States Letters Patent is:

1. A waterproof watch case comprising an annular body having an integral bezel at its upper edge and a back receiving lower edge portion,

said body having on its outer side a ledge portion overhanging the back receiving lower edge portion, a back with an annular upturned flange frictionally seating on the back receiving lower edge portion of the body, a resilient sheet gasket extending across the body and frictionally secured between the annular flange of the back and the back receiving lower edge portion of the body to seal the back to the body, said gasket extending beneath the ledge portion of the body, said upturned flange on the back having an upper knife edge to bear against the gasket and the ledge portion of the body to sever the gasket at said knife edge.

2. A waterproof watch case comprising an annular body having an integral bezel at its upper edge and a back receiving lower edge portion, said body having on its outer side a ledge portion overhanging the back receiving lower edge portion, a back with an annular upturned flange frictionally seating on the back receiving lower edge portion of the body, a resilient sheet gasket extending across the body and frictionally secured between the annular flange of the back and the back receiving lower edge portion of the body to seal the back to the body, said gasket extending beneath the ledge portion of the body, said upturned flange on the back having an upper knife edge to bear against the gasket and the ledge portion of the body to sever the gasket at said knife edge, a stem receiving crown bushing extending through the body, and a spring pad movement holder adapted to fit in the body and press against the gasket biasing it toward the back.

3. A waterproof watch case comprising an annular body having an integral bezel at its upper edge and a back receiving lower edge portion, said body having on its outer side a ledge portion overhanging the back receiving lower edge portion, a back with an annular upturned flange frictionally seating on the back receiving lower edge portion of the body, a resilient sheet gasket extending across the body and frictionally secured between the annular flange of the back and the back receiving lower edge portion of the body to seal the back to the body, said gasket extending beneath the ledge portion of the body, said upturned flange on the back having an upper knife edge to bear against the gasket and the ledge portion of the body to sever the gasket at said knife edge, a stem receiving crown bushing extending through the body, and a spring pad movement holder adapted to fit in the body and press against the gasket biasing it toward the back, said movement holder being a ring with an upturned outer peripheral edge and spaced downwardly bent ears projecting from the inner peripheral edge of the ring for gasket abutment.

4. A waterproof watch case comprising an annular body having an integral bezel at its upper edge and a back receiving lower edge portion, said body having on its outer side a ledge portion overhanging the back receiving lower edge portion, a back with an annular upturned flange frictionally seating on the back receiving lower edge portion of the body, a resilient sheet gasket extending across the body and frictionally secured between the annular flange of the back and the back receiving lower edge portion of the body to seal the back to the body, said gasket extending beneath the ledge portion of the body,

5 said upturned flange on the back having an upper knife edge to bear against the gasket and the ledge portion of the body to sever the gasket at said knife edge, said gasket being of thermoplastic material and said back receiving lower edge portion of the body being arcuately curved to press the gasket against the inside of the upturned flange of the back at the point of tangency.

10 6. A waterproof watch case comprising an annular body having an integral bezel at its upper edge and a back receiving lower edge portion, said body having on its outer side a ledge portion overhanging the back receiving lower edge portion, a back with an annular upturned flange frictionally seating on the back receiving lower edge portion of the body, a resilient sheet gasket extending across the body and frictionally secured between the annular flange of the back and the back receiving lower edge portion of the body to seal the back to the body, said gasket extending beneath the ledge portion of the body, said upturned flange on the back having an upper knife edge to bear against the gasket and the ledge portion of the body to sever the gasket at said knife edge, a stem receiving crown bushing extending through the body, and a spring pad movement holder adapted to fit in the body and press against the gasket biasing it toward the back, said gasket being of thermoplastic material and said back receiving lower edge portion of the body being arcuately curved to press the gasket against the inside of the upturned flange of the back at the point of tangency.

15 7. A waterproof watch case comprising an annular body having an integral bezel at its upper edge and a back receiving lower edge portion, said body having on its outer side a ledge portion overhanging the back receiving lower edge portion, a back with an annular upturned flange frictionally seating on the back receiving lower edge portion of the body, a resilient sheet gasket extending across the body and frictionally secured between the annular flange of the back and the back receiving lower edge portion of the body to seal the back to the body, said gasket extending beneath the ledge portion of the body, said upturned flange on the back having an upper knife edge to bear against the gasket and the ledge portion of the body to sever the gasket at said knife edge, a stem receiving crown bushing extending through the body, and a spring pad movement holder adapted to fit in the body and press against the gasket biasing it toward the back, said movement holder being a ring with an upturned outer peripheral edge and spaced downwardly bent ears projecting from the inner peripheral edge of the ring for gasket abutment, said gasket being of Vinylite and the back being of stainless steel, said back receiving lower edge portion of the body being arcuately curved to press the gasket against the inside of the upturned flange of the back at the point of tangency.

20 65 HYMAN DINSTMAN.
